UNITED STATES PATENT OFFICE

2,550,407

FIGURE TOY

Robert Earl Dorshaw, Philadelphia, Pa.

Application January 7, 1947, Serial No. 720,501

2 Claims. (Cl. 46—116)

1

My invention relates to a new, useful and amusing novelty receptacle and has for one of its objects to associate a jointed image or figure with the cover of a receptacle whereby when said cover, or a portion thereof, is opened and closed, the image, or a section or sections thereof will move to various positions thereby giving an animated appearance to the figure or image.

Another object of this invention is to provide a jointed image having a portion or section thereof mounted on a stationary device and another or other portions resting on a movable device contiguous said stationary device which when the latter is moved, will impart movements to said other portion or portions of the image.

A further object of the present invention is to provide the combination with a receptacle having a swingingly mounted lid, of a jointed image so mounted that the movements of the lid will impart movements to the image whereby the latter will function, in some respect, similar to the subject of which the image is a likeness.

A still further object of the invention is to provide a jointed image having a portion fixed, at least temporarily, to a surface and having another or other portions resting on another and swingingly movable surface to impart an animated appearance to the image as the movable surface is actuated.

With the above and other objects in view this invention consists of the details of construction and combination of elements hereinafter set forth and then designated by the claims.

In order that those skilled in the art to which this invention appertains may understand how to make and use the same, I will describe one embodiment thereof in detail, referring by numerals, to the accompanying drawings forming a part hereof, in which:

Fig. 1 is an isometric view of a novelty receptacle in a closed position and constructed in accordance with my invention.

Fig. 2 is an enlarged side view thereof in an open position.

Fig. 3 is a sectional view of the same in the closed position, and

Fig. 4 is a top plan view of the device.

In carrying out the invention as herein embodied 5 represents the body of a receptacle of any suitable size, configuration or design and for purposes of illustration only said receptacle body is shown as including a bottom 6, side walls 7, a front wall 8 and a rear wall 9. On top of the rear and side walls is mounted a partial top or closure 10 which provides a normally station-

ary surface for a purpose to be presently described. Inside of the receptacle body is mounted a partition 11, the outer surface of which is flush or in line with the inner edge of the partial top or closure 10 to provide a storage chamber 12 for cigarettes, cigars, candies, cakes, jewelry or any other goods or items according to the desires of manufacturers, storekeepers or the users.

Pivotedly hinged or otherwise hingedly or 10 swingingly connected to the normally stationary partial closure or top 10 is a movable closure or lid 13 which, for purposes of illustration only, is shown as having cut-out notches 14 at the sides for the reception of the ears 15 projecting from 15 the ends of the partial closure or top 10 with pins 16 projected through said ears and into the lid 13.

The jointed image 17 which is herein shown as representing a dog is used for illustration only and may be the image of a human being, either 20 real or fabled, any animal, either real or fanciful, denizen of the ocean, insect, reptile, bird or other suitable subject. The image 17 preferably includes three sections, viz., a rear section 18, an intermediate section 19 and a front section 20, 25 as well as an appendage section 21.

The rear section 18 is mounted in a normally stationary position on the partial closure or top 10, as the stationary surface, by a suitable connecting agency, such as dowels 22. An end of 30 the intermediate section 19 is pivotally connected to the rear section 18 by a pivot pin 23 and said pivot pin 23 is positioned in an angular location above and to the rear of the position of the pivot pin or hinge point 16. The opposite or forward end of the intermediate section merely rests on the swinging closure or lid 13 as the movable surface, so that a relative movement occurs between the parts 13 and 19 as they both move in different arcs about their respective pivot points. 35 The front section 20 is pivoted at its rear end to the forward end of the intermediate section by a pivot pin 24 which is normally to the rear of and above the forward edge of the swinging lid 13 and the forward portion of said front section 40 merely rests on the swinging lid or movable surface.

From the foregoing it will be apparent that as the swinging lid 13 is swung about its hinge or pivot point it will swing or elevate the intermediate and front sections of the image in the 50 same general direction but in a different arc so that the intermediate section will seemingly ascend or creep up the movable surface and assume an upright position and the front section will do likewise and finally partially extend over the edge 55

of the swinging lid or movable surface due to gravity.

The swinging lid or movable surface may be actuated in any suitable manner but for purposes of illustration, the appendage 21 is shown as pivoted to the rear section 18 of the image by the pivot pin 25. One end of a connector 26, such as a length of wire, is pivotally attached to the appendage section 21 at a point intermediate the ends thereof by a pivot pin 27 and projects 10 through a narrow slot 28 in the back wall 9 into the interior of the receptacle 5. The inner end of the connector 26 is pivotally attached to a tongue 29 by a pivot pin 30, which tongue is fastened to the swinging lid 13 and extends 15 through an aperture 31 in the upper portion of the partition 11.

Considering the specific device shown herein, for purposes of illustration only, the operation is as follows: By depressing the appendage section or tail 21 motion will be transmitted through the connector 26 and the tongue 29 to the swinging lid 13 thus moving the latter from a rest or closed position to some elevated location. This will change the positions of the lid 13 and the intermediate or body and front or head sections relative to one another which will cause the outer end of the lid to finally assume a position inside of the location of the pivot pin 24 and the head 20 will swing over said outer edge of the lid by 30 gravity, as shown in Fig. 2.

Each time the swinging lid 13 is moved away from or towards the closed position the image changes its position giving an animated appearance thereto.

Of course I do not wish to be limited to the exact details of construction herein shown and described as these may be varied within the scope of the appended claims without departing from the spirit of my invention.

Having described the invention what I claim as new and useful is:

1. A device of the character described comprising a normally stationary surface, a movable surface swingingly connected to the stationary surface, a rear section of an image mounted in

a normally stationary position on the stationary surface, an intermediate image section pivoted to the rear section above and back of the location of the connection between said surfaces and having a free end resting on the movable surface, a front image section pivoted to the intermediate section and also having a portion resting on the movable surface, an appendage image section pivoted to the rear section, and means connecting the appendage section and the movable surface whereby said movable surface will impart an animated appearing movement to the image when the appendage image section is actuated.

2. In a device of the kind described, a stationary surface, a swinging surface hingedly connected to said stationary surface, a jointed image mounted on the surfaces and including at least three sections pivoted to one another and constituting rear, body and head elements, said rear section being fixed to the stationary surface and the other sections loosely resting on the swinging surface with the joint between the rear and body sections above and to the rear of the hinge so that as said swinging surface is moved up and down and the head section adapted to pass off and swing over the edge of said swinging surface as the latter is elevated to approximately its highest limit, and means to actuate said swinging surface.

ROBERT EARL DORSHAW.
